Howard A. Smith,
HIS ATTORNEY

UNITED STATES PATENT OFFICE.

PERLE E. BEASON, OF SPRINGFIELD, OHIO.

SPARK PLUG.

Application filed March 31, 1925. Serial No. 19,725.

This invention relates to new and useful improvements in spark plugs.

It is one of the principal objects of my invention to provide a spark plug in which oil will not accumulate at the firing points to foul it, but will be removed by the suction and compression effected by the moving piston of the engine.

It is another object of my invention to provide means for shedding water from the top of the spark plug so that it will not run down its sides to short circuit it.

A still further object of my invention is to provide for the lower end of the central electrode of the spark plug, a star or pointed contact piece to prolong the life of the firing points.

It is still a further object of the invention to provide a spark plug shell whose lower end is extremely thin to permit the heat of the engine to burn off quickly any carbon that may stick to it.

Other important and incidental objects will be brought out in the following specification and particularly set forth in the subjoined claims.

In the accompanying drawings, Figure 1 is a side view of my improved spark plug. Figure 2 is a longitudinal sectional view taken through the central portion of the plug. Figure 3 is a bottom plan view of my spark plug, showing the six-point star contact piece. And Figure 4 is an enlarged sectional view taken longitudinally through the lower end of the plug.

Referring to the accompanying drawings for a detailed description of my invention, the numeral 1 designates a spark plug shell which is preferably constructed of special aluminum alloy. This shell has an upper hexagonal portion 2 and a downwardly projecting stem 3 which is tapering and threaded externally adjacent the hexagonal part 2 of the plug. (See Figure 1.)

The top part of the hexagonal portion 2 of the plug is recessed to receive a split lock washer 4 upon which seats the lower end of a sleeve cap 5 preferably constructed of porcelain. This cap preferably has an elongated neck and a dome-shaped head 6 which is formed with an overhanging rim or ledge 7 to shed water directly upon the hexagonal portion 2 of the plug and thus to prevent the water from running down the sides of the

cap to short circuit the plug. (See Figures 55 1 and 2.)

The neck of the cap 5 is formed with a wide central bore 8 which tapers at its upper end to a counterbore 9 of small diameter that projects through the head 6 of the cap. Insertible through the lower end of the shell 1 into the bore 8 of the cap 5, is an elongated sleeve 10 preferably constructed of porcelain. This sleeve is formed at its lower end with a shoulder 11 from which it tapers inwardly to its bottom. Located between the shoulder 11 of the sleeve 10 and the top of a recess formed in the lower end of the shell 1, are preferably two annular hollow gaskets 12, 12 that are preferably formed of flexible material for compression when the sleeve 10 is forced inwardly by means soon to be described.

Adapted to be inserted through the sleeve 10 and the cap 5 is a central electrode 13 which is threaded at its top end to receive an assembly nut 14 and a top thumb nut 15. This electrode is also threaded at its lower end to receive a stem extension nut 16 which bears against the top of a tapering recess 17 80 formed in the lower end of the sleeve 10. (See Figures 2 and 4.)

Secured between the extension nut 16 and a rivet head 18 formed on the lower end of the electrode 13, is a convex contact piece 85 19 that is preferably in the form of a six pointed star. (See Figures 3 and 4.) The pointed ends of this contact piece 19 when the plug is assembled, project upwardly to points sufficiently near the lower end of the 90 shell 1 to form spark gaps for the electric current. A large number of firing points is thus provided to prolong the life of the firing part of the spark plug.

The wall of the lower part of the stem 3 95 of the shell 1 surrounding the tapering lower end of the sleeve 10 is very thin so that it may be sufficiently heated by the engine to burn off any carbon that may adhere to it.

Formed in the lower end of the stem 3 of the shell 1 is a circumferential series of holes 20 through which oil is free to escape from the space between the wall of the lower end of the stem 3 of the shell and the lower end 105 of the sleeve 10. When the engine is in operation, any oil which remains within this space will be withdrawn from it through the

holes 20 in the shell by the compression and suction effected by the moving piston. It is thus seen that in my improved spark plug no oil will remain on the firing points to interfere with the explosion of the charge.

Another feature of advantage of my spark plug is that it is assembled from the bottom, after which the parts are tightly drawn together by the assembly nut 14.

Having described my invention, I claim:

A spark plug comprising a metal shell, an insulating sleeve within the shell, formed at

its lower end with a shoulder, an annular flexible packing between the said shoulder and the shell, a central electrode passing through said sleeve, and means on said electrode to compress said packing, the wall of the shell below and near said packing being formed with a circumferential series of holes to exude oil from the packing when it is compressed.

In testimony whereof I have hereunto set my hand this 28th day of March, 1925.

PERLE E. BEASON.
